(57) **CLAIM**

The ornamental design for a thermal pack, as substantially shown and described.

DESCRIPTION

FIG. 1 is a perspective view of a thermal pack showing the new design;
FIG. 2 is a front elevation view thereof;

FIG. 3 is a rear elevation view thereof;

FIG. 4 is a top plan view thereof;

FIG. 5 is a bottom plan view thereof;

FIG. 6 is a left-side elevation view thereof; and,

FIG. 7 is a right-side elevation view thereof.

The spheres or beads illustrated in the drawings are drawn so as to appear as transparent or semi-transparent. The baffle illustrated is formed of two transparent pack walls, sealed together to form a thin, flat, planar surface as illustrated in the drawings. The shading lines indicate the clear or transparent nature of the baffle. The bead shown in solid lines in FIGS. 1-3 is located in the middle of the thermal pack, equidistant from the front and rear pack walls. Structure illustrated in broken lines is not otherwise part of the claimed design.
